UNITED STATES PATENT OFFICE.

WILLIAM M. BACON, OF CHICAGO, ILLINOIS, ASSIGNOR OF ONE-HALF TO FREDERICK W. MITCHELL, OF CHICAGO, ILLINOIS.

PRINTING-MACHINE.

1,320,358.

Specification of Letters Patent. Patented Oct. 28, 1919.

Application filed April 17, 1918. Serial No. 229,062.

To all whom it may concern:

Be it known that I, WILLIAM M. BACON, a citizen of the United States, residing at Chicago, Cook county, Illinois, have invented a new and useful Printing-Machine, of which the following is a specification.

This invention relates to improvements in printing machines and more particularly to printing machines adapted to print with paint upon metal, wood or fabric to produce relatively large signs or work of a similar character.

An object of the invention is to provide a printing machine including a platen and printing drum arranged for adjustment to receive material of varying widths and thickness for printing impressions, in combination with continuous feed mechanism for advancing the work to the printing point, and mechanism for discharging the work from the printing point including also inking mechanism; all of said mechanisms being operated from a common source of power.

Another object of the invention is to provide a printing machine including printing mechanism comprising a pair of revoluble cylinders, one carrying the printing type and the other constituting a platen, with means for adjusting the space between said cylinders whereby material of different thickness is received at the printing point for printing impressions.

Another object of the invention is to provide in a printing machine a form of feeding mechanism whereby material of varying widths and thickness may be continuously advanced to the printing point for receiving printed impressions.

Additional features and advantages attainable from the invention will be readily recognized without specific mention from the following detailed description of the invention, taken in connection with the accompanying drawings, in which—

Figure 1 is a broken plan view of the printing machine embodying the invention.

Fig. 2 is a broken side elevation of the machine.

Fig. 3 is a cross section through the machine taken substantially on the line 3—3 of Fig. 2.

Fig. 4 is a detailed view illustrating the guiding mechanism for feeding the work

between the printing cylinders after it has been moved toward the printing point by the feeding mechanism.

In the embodiment of the invention illustrated in the drawings the machine comprises an open metal frame including corner standards 1 preferably composed of angle iron, said standards supporting a lower rectangular frame 2 and an upper frame 3. Approximately centrally disposed and rising at the side of the frame are heavy standards 4 constructed preferably of I-beams.

The motor M for operating the machine is mounted on a standard 5 extending transversely of the machine and carried by the side members of the lower frame 2.

Extending transversely and lying within the frame is a cylinder 6 supported upon a shaft 7, the shaft 7 being journaled at each end in movable bearings 8 slidably mounted in openings 9 in the web of the standards 4. The bearings 8 are raised and lowered by bearing adjusting mechanism of known construction which is operated by the hand rod 10. The cylinder 6 constitutes the platen upon which the work is fed to receive printing impressions from the printing roller. As it is desirable to adapt the machine to receive material of various thickness and to adjust the pressure of the work against the printing cylinder, the machine has been arranged so that by the operation of the hand rod 10 an extremely accurate adjustment of the shaft 7 may be effected.

The type cylinder 11 is carried on a shaft 12 which is journaled at each end in permanently adjusted bearings 13 mounted at the top of the standards 4. The axis of the shaft 12 is in parallel vertical alinement with the axis of the shaft 7 and since the shaft 7 is adjustable vertically the space between the proximate peripheries of the cylinders 6 and 11 may be varied as required for receiving the work at the printing point of varying thickness, so that regardless of the thickness of the work a uniform pressure is exerted thereon to effect the printing as it passes between said cylinders 6 and 11 at the printing point. The mechanism for rotating the cylinders 6 and 11 in synchronism comprises a pinion 14 attached to the drive shaft 15 of the motor which extends beyond the frame work at one side of the machine. The pinion 14 meshes with and

drives a large gear wheel 16 which is fast on an extended end of the shaft 7.

An intermediate pair of gears are arranged in a movable bearing 17, said movable bearing being supported at the junction of links 18 and 19, the outer ends of which are respectively pivoted upon shafts 7 and 12. The pair of intermediate gears are mounted upon a common shaft 20 which is 10 revolubly mounted in the adjustable bearing 17. The pair of gears are in parallel vertical planes and the inner one 21 of said gears meshes with the large gear 16 and the outer one 22 of said pair of gears meshes 15 with a gear 23 which is mounted upon the link 19, the gear 23 in turn meshing with and driving a gear 24 secured to an extension of the shaft 12. The gear 24 has a releasable connection with the shaft 12 in the 20 form of an adjustable cone clutch 25 of known construction. The gear 24 is arranged so that it may be rotated in adjusting operations without rotating the shaft 12 and thereby the cylinder 11, so that after 25 the adjustment is effected the gear wheel may be locked to the shaft 12.

It will be observed that the drive connection whereby the shaft 12 is driven permits the elevation of the axis of the shaft 7 to be 30 changed without throwing out of mesh the driving connection between the two cylinders. Obviously as the shaft 7 is lowered the axes of the pair of gears 21 and 22 are drawn inwardly, preserving the meshing engagement between the gear 21 and the gear 16, the normal adjustment of the axes of the gears 22 and 23 and between the axes of the gear 23 and gear 24. By this arrangement 35 it will be seen that the two cylinders 6 and 11 may be driven in synchronism regardless of the adjustment of the shaft 7 upon which the cylinder 6 is supported.

The mechanism for feeding the work to the printing point between the cylinders 45 comprises an endless belt or chain 26 which operates over alined sprockets 27 and 28, said sprockets being carried respectively by shafts 29 and 30 journaled in bearings 31 and 32 on the upper face of the frame 3. 50 The shaft 29 is disposed near one end of the frame and the shaft 30 is arranged in parallel alinement therewith but near the printing cylinders. The sprockets 27 and 28 are arranged so that the endless belt or chain 26 55 extends longitudinally with the frame of the machine at a position intermediate of the width of the machine. At one side of the belt 26 is a series of permanently fixed revoluble rollers 33, said rollers being arranged in supports with the axes thereof parallel in a horizontal plane and inclining forwardly toward the right hand side of the machine. At the right hand side of the belt 60 65 26 is a second series of rollers 34 which are in a laterally adjustable support comprising

side members 35 and end members 36, the end members 36 being adjustably supported by cross bars 37 carried by the frame of the machine. Thus the entire frame in which the rollers 34 are supported may be moved 70 toward and away from the belt 26 so that the feeding mechanism is adapted to receive material of different widths. When the adjustment has been effected the support may be locked in position by set screws 38, 75 which lock the end members 36 of the roller supporting frame with the bars 37. The rollers 34 are arranged in the same horizontal plane with the rollers 33 and have their axes inclined outwardly toward the right 80 hand side of the machine at the same angle of inclination as the axes of the rollers 33.

At the outer side of the movable frame in which the rollers 34 are supported is a vertically disposed guide strip 39 for guiding the edge of the work as it is fed by the feeding mechanism to the printing rollers. The belt 26 carries a number of adjustable lugs 40 which contact with the forward end of the flat sheets of work when the same 90 are placed upon the rollers 33 and 34, the lugs extending above the horizontal plane of the upper surface of the two sets of rollers. As the work is moved forwardly by the inward movement of the belt, exerting pressure upon the front edge of the work through the lugs 40, the flat sheets are moved to the right hand side of the machine against the inner face of the guide strip 39 and at the same time fed inwardly toward 95 the printing point. The feeding mechanism thus automatically adjusts the position of the sheets as they are fed to the printing mechanism so that they will be received for printing impressions under 100 proper alinement and adjustment.

Extending inwardly from the forward end of the frames in which the rollers are supported is a guide plate 41 which inclines upwardly at its inner end so that its inner 110 edge will lie in the same horizontal plane with the periphery of the cylinder 6 at the printing point. In Fig. 4 this mechanism is clearly shown from which view it will be observed that a sheet S of the work, after it leaves the roller, is raised by the guide strip 41 to a horizontal plane coincident with the space between the cylinders 6 and 11. The guide strip 41 has sufficient resiliency so that when the cylinder 6 is lowered the forward 115 end of the strip will be depressed sufficiently to maintain the adjustment between the periphery of the cylinder at the printing point and the inner edge of the guide strip so that regardless of the adjustment of the cylinder 6, the work will always be presented in the proper horizontal plane to be received between the cylinders 6 and 11 at the printing point.

In the rear of the cylinders is a work dis- 130

charging mechanism comprising a number of longitudinally disposed and parallel aligned belts 42 which operate over rollers 43 supported on shafts 44 journaled in brackets 45 mounted on the upper face of the frame of the machine. Both the belt 26 and the belts 42 are moved in the same direction, that is from the forward end of the machine toward the rear thereof, by driving mechanism comprising a gear 46 which meshes with the large gear wheel 16, the gear 46 in turn meshing with and driving a pinion 47 fast on the forward one of the shafts 44, thereby rotating said shaft 44. The shaft 44 carries a sprocket wheel 48, and the inner one of the shafts 30 carries a sprocket wheel 49. A belt connection 50 operating over the sprockets 48 and 49 provides a power connection whereby the said shaft 30 is driven from the shaft 44, thus both the feeding mechanism and the discharge mechanism are operated together in the same direction and at the same rate of travel.

25 The mechanism for inking the printing cylinder is located in front of the forward face of the cylinder and comprises a pair of inking rollers 51 and 52, the roller 52 operating in an ink trough 53. The inking mechanism is driven through a chain of connections with the gear 24 comprising a pinion 54 mounted on a shaft 55 supported in brackets 56, the sprocket 54 in turn driving a sprocket chain 57 which rotates a sprocket 58 secured to the roller shaft 59.

I am aware that the embodiment of the invention may be modified in various particulars without departing from the spirit and scope of the invention. I do not limit myself therefore to the exact construction shown and described, but what I claim and desire to secure by Letters Patent, is:—

1. In a printing machine, the combination with printing mechanism comprising a printing cylinder and a platen, and inking mechanism for the printing cylinder, of a series of rollers for supporting the work during movement of the work into the space between the printing cylinder and the platen, a work actuating device for moving the work on said rollers to the printing cylinder and platen, and means for driving said cylinder, said platen, said inking mechanism and said actuating devices from a common source of power.

2. In a printing machine, the combination with printing mechanism comprising a printing cylinder and a platen, and inking mechanism for applying ink to the printing cylinder, of a series of rollers having their upper surfaces in approximately the same horizontal plane as the space between the printing cylinder and the platen, a work actuating device, mechanism for operating said printing cylinder, said platen and said

inking mechanism, means driven by said operating mechanism for operating the work actuating device to move the work on said rollers between the printing cylinder and the platen, and a guide for guiding the work properly toward the printing cylinder and the platen.

3. In a printing machine, the combination with printing mechanism comprising the printing cylinder and a platen, and inking mechanism for said printing cylinder, of a series of work supporting rollers whose axes are inclined relative to the axis of the printing cylinder, a work actuating device, means for operating said printing mechanism, connections driven by said operating means for operating said work actuating device to carry the work to the space between the printing cylinder and the platen, and a guide for guiding the work properly as the work is moved by said device.

4. In a printing machine, the combination with printing mechanism comprising a printing cylinder and a platen, said printing cylinder and platen being arranged to receive the work therebetween, and inking mechanism for said printing cylinder, of a series of rollers having their peripheries in the same horizontal plane and approximately in the same plane as the space between the printing cylinder and the platen, said rollers being arranged to guide the work toward one edge of the machine, a guide strip running vertically at one side of said rollers for guiding the work moved thereagainst by the rollers, a continuously operating actuator for moving the work placed upon said rollers toward the interval between the printing cylinder and the platen, and means for driving said printing cylinder, said platen, said inking mechanism and said actuator from a common source of power.

5. In a printing machine, the combination with printing mechanism comprising a printing cylinder and a platen, said printing cylinder and platen being arranged to receive the work therebetween, and inking mechanism for said printing cylinder, of a series of rollers having their peripheries in the same horizontal plane and approximately in the same plane as the space between the printing cylinder and the platen, said rollers being arranged to guide the work toward one edge of the machine, a guide strip running vertically at one side of said rollers for guiding the work moved thereagainst by the rollers, a continuously operating actuator for moving the work placed upon said rollers toward the interval between the printing cylinder and the platen, means for driving said printing cylinder, said platen, said inking mechanism and said actuator from a common source of power, and a guide at the inner end of said

series of rollers for raising the work as it leaves the rollers and directing it into the space between the printing cylinder and the platen.

- 5 6. In a printing machine, the combination with printing mechanism comprising a printing cylinder and a platen, said printing cylinder and platen being arranged to receive the work therebetween, and inking 70 mechanism for said printing cylinder, of a series of rollers having their peripheries in the same horizontal plane and approximately in the same plane as the space between the printing cylinder and the platen, 75 said rollers being arranged to guide the work toward one edge of the machine, a guide strip running vertically at one side of said rollers, for guiding the work moved thereagainst by the rollers, a continuously operating 80 actuator for moving the work placed upon said rollers toward the interval between the printing cylinder and the platen, means for driving said printing cylinder, said platen, said inking mechanism and said 85 25 actuator from a common source of power, a guide at the inner end of said series of rollers for raising the work as it leaves the rollers and directing it into the space between the printing cylinder and the platen, and a 90 30 device for conveying the work from the machine after it has received printing impressions.

7. In a printing machine, the combination with printing mechanism, inking mechanism, 95 for applying ink to the printing mechanism, and operating mechanism for operating the printing and inking mechanisms, of a series of rollers for supporting the work, a device for moving the work on said rollers to the 100 printing mechanism, and means actuated by said operating mechanism for operating said device to move the work to the printing mechanism.

8. In a printing machine, the combination with printing mechanism, of a series of rollers for supporting the work, a device for moving the work on said rollers to the printing mechanism, mechanism for operating said device to move the work on said rollers 105 to the printing mechanism, means for moving the work past the printing mechanism, and operating mechanism for operating the printing mechanism and said moving means.

9. In a printing machine, the combination with a printing cylinder, a platen for co-operating with the printing cylinder to move the work during the printing operation, and an actuator for operating the printing cylinder and the platen, of a series 110 of rollers for delivering the work to the space between the printing cylinder and the platen, and devices driven by said actuator for moving the work on said rollers.

10. In a printing machine, the combination with a printing cylinder, means for ap-

plying ink to the printing cylinder, and a platen co-operating with the printing cylinder to move the work during the printing operation, of a series of relatively revolute rollers for supporting the work, a device for 70 moving the work on said rollers to the space between the printing cylinder and the platen, means for supporting said rollers in positions in which their axes are inclined relative to the axis of the printing cylinder, 75 and an actuator for actuating the printing cylinder, the platen, the inking means and said device.

11. In a printing machine, the combination with a printing cylinder, means for applying ink to the printing cylinder, and a platen co-operating with the printing cylinder to move the work during the printing operation, of a series of relatively revolute rollers for supporting the work, a device for 80 moving the work on said rollers to the space between the printing cylinder and the platen, means for supporting said rollers in positions in which their axes are inclined relative to the axis of the printing cylinder, 85 90 and an actuator for actuating the printing cylinder, the platen, the inking means, and said device, and a guide for guiding the work as the work is being moved toward the printing cylinder and the platen by said device rollers.

12. In a printing machine, the combination with a printing cylinder, means for applying ink to the printing cylinder, and a platen co-operating with the printing cylinder to move the work during the printing operation, of a series of relatively revolute rollers for supporting the work, a device for moving the work on said rollers to the space between the printing cylinder and the 100 platen, means for supporting said rollers in positions in which their axes are inclined relative to the axis of the printing cylinder, 105 an actuator for actuating the printing cylinder, the platen, the inking means and said 110 device, and a device for conveying the work from the machine after it has been printed.

13. In a printing machine, the combination with a printing cylinder and a platen for co-operating with the printing cylinder to move the work during the printing operation, of a series of rollers for supporting the work during movement of the work to position to be engaged by the printing cylinder and the platen, and mechanism for moving the work on said rollers to position to be engaged by the printing cylinder and the platen.

14. In a printing machine, the combination with a printing cylinder and a platen for co-operating with the printing cylinder to move the work during the printing operation, of a series of rollers for supporting the work, a device for moving the work on said rollers to position to be engaged by the 125 130

printing cylinder and the platen, and means for conveying the work from the machine after the printing operation is complete.

15. In a printing machine, the combination with a printing cylinder, and inking mechanism for applying ink to the printing cylinder, of a series of rollers for supporting the work during movement of the work into engagement with the printing cylinder, 10 and a work actuator for moving the work on said rollers into engagement with the printing cylinder.

16. In a printing machine, the combination with a printing cylinder, and inking mechanism for applying ink to the printing cylinder, of a series of rollers for supporting the work during movement of the work into engagement with the printing cylinder, an actuator for moving the work 15 on the rollers toward the printing cylinder, and a device for conveying the work from the machine after the printing operation is completed.

17. In a printing machine, the combina-

tion with a printing cylinder, of a series of 25 rollers for supporting the work during movement of the work into engagement with the printing cylinder, a device for conveying the work from the machine after the printing operation has been completed, and 30 actuating mechanism for concurrently moving the work toward the printing cylinder and operating the printing cylinder and said conveying device.

18. In a printing machine, the combination with a printing cylinder, a platen, a device for applying ink to the printing cylinder, a series of rollers for supporting the work, a device for moving the work on said rollers to position to be engaged by the 40 printing cylinder and the platen, and a conveyer for conveying the work from the machine after the printing operation is complete, of actuating mechanism for operating concurrently said printing cylinder, said 45 platen, said inking device, said moving device and said conveyer.

WILLIAM M. BACON.
